UNITED STATES PATENT OFFICE

WALLACE W. DE LANEY, OF NEW HAVEN, CONNECTICUT, ASSIGNOR TO THE SEAMLESS RUBBER COMPANY, INC., OF NEW HAVEN, CONNECTICUT, A CORPORATION OF MASSACHUSETTS

DESIGN FOR RUBBER SHEETING OR LIKE ARTICLE

Application filed January 29, 1931. Serial No. 38,475. Term of patent 14 years.

To all whom it may concern:

Be it known that I, WALLACE W. DE LANEY, a citizen of the United States, residing in New Haven, in the county of New Haven and State of Connecticut, have invented a new, original, and ornamental Design for Rubber Sheet or Like Article, of which the following is a specification when taken in connection with the accompanying drawing, in which is shown a face view of a piece of sheet rubber showing my new design.

I claim:

The ornamental design for rubber sheeting or like article substantially as shown.

WALLACE W. DE LANEY.
